UNITED STATES PATENT OFFICE.

FRANCIS O. HANSON, OF CHICAGO, ILLINOIS.

FIREPROOF STAIRWAY.

No. 802,506.

Specification of Letters Patent.

Patented Oct. 24, 1905.

Application filed May 10, 1905. Serial No. 259,840.

To all whom it may concern:

Be it known that I, FRANCIS O. HANSON, a citizen of the United States, residing at Chicago, in the county of Cook and State of Illinois, have invented certain new and useful Improvements in Fireproof Stairways, of which the following is a full, clear, and exact specification.

My invention relates more particularly to 10 the class of fireproof stairways composed of metallic members bolted or otherwise secured together in combination with a concrete or other fireproof filling to constitute the body of the step; and it has for its primary object 15 to provide an improved form of fireproof stairway which will be light and consequently economical in construction, and at the same time will possess the maximum degree of strength, the further object being to make a 20 stairway of the desired character of knocked-down form, so that the various parts may be shipped to the place of use in a compact form, also avoiding the liability of breakage, and 25 readily set up without requiring any special degree of skill.

With a view to the attainment of these ends and the accomplishment of certain other objects that will hereinafter appear the invention consists in the features of novelty in the 30 construction, combination, and arrangement of parts, which will now be described with reference to the accompanying drawings and more particularly pointed out in the claims.

In the said drawings, Figure 1 is a vertical 35 longitudinal sectional view of a stairway constructed according to my invention, and Fig. 2 is a vertical cross-section thereof with the concrete omitted.

In carrying out my invention I employ the 40 usual side stringers A, which may be composed of cast-iron or any other suitable material and upon which at proper intervals apart are cast, formed, or otherwise attached supporting - lugs B, having their faces arranged in horizontal planes. Upon these lugs B are supported angle-irons C or other suitable connecting members, which tie the stringers A together, the angle-irons being secured in an inverted position upon the lugs 45 B by means of stove-bolts b or any other suitable device. Extending across the stairway between the stringers A are a number of arches D, one for each of the steps. These are bowed upwardly, as distinctly shown in Fig. 50 1, and have their edges attached to the angle- 55

irons C by bolts, rivets, or other suitable devices d and the bolts b, the lower edge of each being attached to the upright flange of the angle-iron, while the upper edge rests upon and is attached to the horizontal angle 60 of the next angle-iron by the bolt b, the edges of the arch D resting against the inner faces of both of the angle-irons. The stringers A are also formed with the lugs E, which have vertical faces for the attachment of the risers F, the 65 attachment being effected by stove-bolts e or other suitable means, with the nuts arranged inside. The upper edge of the riser is formed with a nosing H, extending even with the level of the stair-tread, while the lower end is formed 70 with a return-bend or flange I, located a considerable distance above the upper edge of the arch D. The metallic portion of the stair being thus put together, the space between the arch D and the riser F is then filled with concrete G 75 or any other suitable material, which molds itself to the contour of the arch D and which may be leveled off between the upper edge of the nosing H and the upper surface of the return I to produce a level tread. The concrete 80 G finds its way down into the narrow space between the riser F and the lower end of the arch D, where the concrete constituting the upper edge of the next step below also enters under the return I, and thus constitutes practically a continuation of the concrete filling. With the stair thus constructed 85 it will be seen that the concrete filling assumes an arched formation like the sheet-metal arch D, and consequently after it sets possesses 90 the strength of a perfect arch and aids the arch D in sustaining the weight directly upon the cross connections or angle-irons C, upon which both ends of the concrete filling rest. Consequently I am enabled to save the concrete material that is displaced by an upward 95 arching of the plate D, and thus not only cheapen the construction in that item, but reduce the weight to which the stringers and other metallic members are subjected, and 100 consequently lessen the cost of these parts without detracting from the strength of the structure.

Having thus described my invention, what I claim as new therein, and desire to secure by 105 Letters Patent, is—

1. In a fireproof stairway the combination of the stringers, bars connecting the stringers together, an arched plate extending between the stringers, and a concrete body supported 110

at its upper and lower ends upon said bars and arched upwardly on its under side to conform to said plate.

2. In a fireproof stairway the combination 5 of the stringers, bars connecting the stringers together, risers connecting the stringers and having their lower edges arranged above said bars, plates connecting said bars together and forming cavities with said risers, and concrete 10 fillings in said cavities, the upper portion of one filling being extended below the lower end of the next filling above and under the lower edge of the riser.

3. In a fireproof stairway the combination 15 of the stringers, risers connecting the stringers together and having return-bends at their lower edges, the return-bend of one riser being substantially level with the upper edge of the next riser below, and concrete fillings

constituting the body portion of the steps, 20 extending between said risers and under said return-bends.

4. In a fireproof stairway the combination 25 of the stringers, having lugs, angle-irons detachably secured to said lugs and connecting the stringers together, an arched plate having its lower edge connected to the upright flange of one of said angle-irons and its upper edge connected to the horizontal flange of the next angle-iron above, a riser having its ends 30 detachably secured to the stringers, in front of said arched plate and forming a cavity, and a concrete filling located in said cavity upon said arched plate.

FRANCIS O. HANSON.
